FILM FORMING MACHINE

Charles E. Hetzel, South Hadley Falls, Mass., assignor to Zeloid Products Corporation, Holyoke, Mass., a corporation of Delaware

Substitute for abandoned application Serial No. 137,462, September 24, 1926. This application May 15, 1931, Serial No. 537,591.

1 Claim. (Cl. 18—15)

My invention relates to coating machines and particularly to machines adapted to the coating and coagulation of cellulosic solutions.

An object of my invention is to provide a machine for the production of precipitated sheets of a coagulum of dissolved cellulose.

Another object of my invention is to provide a machine having a coating belt, means for coating a solution of cellulosic material thereon, means for coagulating the cellulose to form a homogeneous cellulosic sheet, and means for cleaning the coating belt preparatory to recoating with more cellulosic solution.

In the prior art of the preparation of transparent homogeneous films of cellulosic material, it has been customary to dissolve the cellulose, as by the well-known "Viscose" process, and then to extrude the viscous solution of cellulose into a bath of dissolved coagulant to form a thread or a sheet. The material was then processed, by treatment in other materials, for further coagulation and purification. Difficulty was, however, experienced in the extrusion of the dissolved cellulose, and in the handling of the sheeted cellulose material in the first coagulating bath. The material is very fragile immediately after the extrusion process, and surface tension effects and similar forces tend to interfere with the production of a smooth, un wrinkled, sheet of uniform thickness. Likewise much difficulty is encountered in the conveying of the sheet from the first coagulating bath to other, successive, treating baths.

My invention hereinafter described in this application, which is a substitute for my former application 137,462 filed September 24, 1926, provides means whereby the cellulosic material is coated upon a belt which provides additional strength and support for the very fragile sheet, until the coagulation has proceeded to an extent such that the sheet has sufficient strength for reasonable handling and transfer to the final coagulating and purifying processes.

By this means I am enabled to produce a much smoother, more uniform, and much stronger sheet of cellulosic material, and I am enabled to remove many of the difficulties of handling, and to avoid much of the delicate care previously necessary.

Other objects and structural details of my invention will be apparent from the following description when read in connection with the accompanying drawing, wherein:

Fig. 1 is a diagrammatic representation in verti-

cal side view of an embodiment of the apparatus of my invention;

Fig. 2 is a vertical front view of the same embodiment;

Fig. 3 is a broken away view of the rollers under the coagulating section of the device, and

Fig. 4 is a perspective view of a broken fragment of the rollers, belt and coagulum of the device.

Referring to Figs. 1 and 2, I provide a continuous belt 1 which may conveniently be of metal, and which may conveniently be plated with a tarnish proof surfacing material, such as gold, or chromium, or Monel metal alloy, or other corrosion resistant material. Alternatively the belt may be made of such material as stainless steel, or it may be of a non-metallic material such as rubber. The belt is carried and traversed by a plurality of rolls 2, 3, 4, 5, 6 and 7 as indicated, which keep it under moderate tension.

Provision is made for applying to the belt a coating of the cellulose solution. The provision may consist of a coating roll 8 as shown bearing against the outer surface of the belt, which is supplied with the cellulose solution by an additional roll 9, rotating in a tank 11 of cellulosic solution as indicated. Or alternatively the lower arc of the roller 2, may be adapted to dip into a bath of the cellulose solution, or other well-known means may be provided for the application of a coating of the cellulose solution to the belt, according to the thickness of coating required. The belt is carried upward from the coating device for a distance, chosen according to the thickness of coating desired. In the course of the upward travel, excess material drains downward and off at a speed depending upon the rate of travel of the belt and the viscosity of the solution. Likewise any air bubbles in the solution come to the surface and burst, and surface tension forces smooth out any differences in thickness which might exist in the coating as it leaves the coating device. During the upward travel also the solution stiffens, and sets slightly or "jels" and by the time it has reached the end of the upward travel, part, or all, of its fluidity has been lost.

At the end of the vertical travel the belt is drawn over a top roll 4, and through a period of horizontal travel to another top roll 5. During this period of horizontal travel, the surface tension forces complete the smoothing out of the coating and cause it to become of a very uniform thickness. The coated sheet is then drawn over the roll 5, in a line of travel along a downward slope.

A coagulating solution is provided by a supply means which may be a roller 12, and applied to the coating of cellulose solution close to the top roll 5. A supply of coagulant is maintained in a tank 14

5 and supplied therefrom to the roller 12. The coagulating solution flows downward with the travel of the coated belt and causes the preliminary coagulation of the coating while it is still on the belt.

10 Rolls 15 are provided for supporting the belt during this downward sloping travel. These rolls are desirably made with enlarged ends, that is, with the diameter substantially greater for a short distance from the ends as shown in Figs. 3 15 and 4. They serve to raise the edges of the belt above the center portion and thereby prevent the coagulating solution from running over the sides and onto the back of the belt. In order that an undue strain may not be put upon the belt, it is desirable that either the top roll 5 or the following roll 6 be slightly reduced in diameter at its ends.

20 After the application of the coagulating solution and a period of downward travel, the belt is drawn around another roller 6. The application of the coagulant tends to destroy the adhesion between the coating and the belt, and during the period of downward travel sufficient coagulation occurs, not only to free the sheet from the coating belt but to develop a substantial strength in the cellulose coating itself. The coated sheet is thus readily removable from the coating belt and such removal is therefore effected at or before the material reaches the roll 6 by the action of the 25 feed rollers 6a of a vat 6b. The belt being drawn around the roll 6 readily releases the partially coagulated coating. The coated sheet is then drawn into the sequence of vats for the complete coagulation and purification of the sheet.

30 40 After being drawn around the roller 6 the coating belt is drawn between a series of cleaning and polishing rolls 16 which remove traces of cellulose solution and traces of coagulant, and

leave the belt in clean condition for re-coating. The cleaning rolls may be arranged in a single series as shown, or they may be broken up into several series, by an additional tensioning roll, which may, if desired, be mounted upon guides with a spring pressure to maintain constant tension upon the belt without regard to temperature changes, or to inequalities in the structure. The coating belt is then delivered from the cleaning rolls to the bottom roll 7 after which it may be 10 re-coated, and returned through the previously described cycle.

15 The operation of my device thus allows full play to the surface tension forces and makes optimum utilization of them for the production of 15 a smooth, unrinkled sheet of material of uniform thickness. It likewise allows convenient application of the coagulating solution, and permits the delivery of a sheet of partially coagulated material which is of substantial strength and 20 adapted to easy handling through the following and finishing processes.

25 By the apparatus of my invention I am thus enabled to produce a sheet of cellulosic material, of superior strength, superior uniformity of 25 thickness, and superior smoothness.

30 While I have shown but a single embodiment of my invention in the accompanying description it is capable of various modifications therefrom without departing from the spirit thereof and it 30 is desired, therefore, that only such limitations shall be imposed thereon as are required by the prior art or indicated by the appended claim.

I claim:

35 In combination, a coating carrying belt, 35 processing means comprising means for the application of material thereto, and means for removing processed materials from said belt, means for minimizing the transfer of material to the back of said belt, means for cleaning the coating 40 surface of said belt and additional means for cleaning the back surface of said belt.

CHARLES E. HETZEL.
